UNITED STATES PATENT OFFICE.

JOSEPH RISSEL, OF LAWRENCEBURG, INDIANA.

IMPROVEMENT IN SUSPENSION SAFES OR SIDEBOARDS.

Specification forming part of Letters Patent No. 146,711, dated January 20, 1874; application filed December 17, 1873.

To all whom it may concern:

Be it known that I, JOSEPH RISSEL, of Lawrenceburg, Dearborn county, Indiana, have invented a new and useful Suspension Safe or Sideboard, of which the following is a specification:

My invention relates to a safe or sideboard for containing provisions of any kind, which safe consists, essentially, of one or more shelves or tables, secured to a hollow shaft, that is capable of sliding freely upon a rod or pipe depending from the ceiling of the room wherein the sideboard is located. Secured to the aforesaid tubular shaft are ropes, which, after passing around suitable sheaves, have counterbalancing-weights attached to them, so as to render the elevating and lowering of the safe a comparatively easy and certain operation. Accidental lowering of the safe is prevented by means of a spring bolt or catch, that is secured to the table-shaft, and is adapted to engage with either one of a series of notches cut in the fixed rod that depends from the ceiling.

During the summer season, the shelf or shelves may be surrounded with a suitable screen, composed of mosquito-bar, wire-gauze, or any other material that will protect the contents of the safe from the depredations or defilments of insects, &c.

Figure 1 is a vertical section of my suspension-safe in its lowered or depressed position, the screen being removed. Fig. 2 is a similar section, showing the safe elevated and surrounded with the screen. Fig. 3 is an enlarged transverse section through the hollow shaft and inclosed notched rod in the plane of the spring-bolt, and Fig. 4 is an axial section through a modified form of my safe.

A represents the ceiling of a room, from which depends a rigid bar or pipe, B, of any suitable length, say from three to five feet, according to the height of said ceiling. This fixed rod is provided with a series of notches or recesses, b, for a purpose which will presently appear. Adapted to rotate around this notched rod, and also to move freely up and down on the same, is a tubular shaft or stem, C, having a collar, c, at its upper end, and another one, c', near its lower end. Secured to this hollow shaft, between its lower collar c' and the fixed annulus D, is a shelf or table, E,

preferably round, although it may be of any other convenient shape. Attached to the under side of the shelf E are sockets F, to which are pivoted, at f, swinging legs G, that are capable of being turned up to the horizontal position shown in Fig. 2. Each socket is perforated for the reception of a pin, g, which serves to maintain the leg G either in its vertical or horizontal position. Projecting downwardly from the annulus D are handles d, which enable the shaft C to be rotated when in its elevated position. Attached to the hollow shaft C, near the upper end thereof, is the case or housing h of a spring bolt or catch, H, whose inner end is adapted to engage with either of the notches b. Resting upon the housing h is a disk, I, having a circumferential groove, i, for the reception of the upper and gathered portion of a screen, J, which may be confined within said groove by the cord or elastic band j. Another band or draw-string, j', confines the lower portion of the screen around the table, so as to effectually exclude insects from the provisions placed upon said shelf. Located between the disk I and upper collar c is a ring, K, from which radiate two diametrically-opposite arms, k k', whose ends terminate in eyes l l'. Attached to these eyes are ropes L L', which, after being rove around sheaves M M', have weights or other counter-balances N N' applied to them.

In order to confine these counter-balances to a vertical path when they are raised and lowered, I provide them with guiding-rings n n', through which the ropes L L' pass, as clearly shown in Fig. 1. The sheaves M M' are journaled in arms O O', which may be maintained at any desired elevation upon the fixed rod B by set-screw o.

When my suspension-safe is lowered, so as to allow provisions to be placed upon the shelf E, or to be removed therefrom, the legs G are secured in an erect position, and rest upon the floor of the room, the screen J having been first entirely removed or drawn aside. In this depressed position of the sideboard, the spring-bolt H engages with the lowermost of the notches b, and thereby prevents the shelf descending any farther, in case the legs thereof should be accidentally sprung inwardly. In this lowered position, the shelf E should be about on a level

with an ordinary table, so as to be conveniently reached, and turned around, if necessary.

When it is desired to elevate the safe, the screen J is applied to the disk I and drawn tight around the shelf E, after which the legs G are folded up and secured in a horizontal position. The safe is then elevated bodily, care being taken to keep the spring-bolt H in the same plane as the notches b, and when the desired elevation has been attained, said bolt is allowed to engage with the proper notch, and thereby maintain the safe securely in position.

Owing to the provision of counter-balances N N', the act of elevating the safe and its contents is a very easy one, and can be accomplished in a few moments. To again lower the safe, it is necessary first to rotate the shaft C either to the right or left, so as to disengage its catch H from the supporting-notch, after which the table is allowed to descend without hinderance, on account of said catch traversing the smooth or unnotched side of the bar B.

Having descended as far as desired, the shaft C is then rotated in a reverse direction, so as to bring its catch in line with the notches b. The engaged position of the aforesaid catch is clearly shown in Fig. 3, and its unslipped or disengaged position indicated therein with dotted lines. The handles d enable the shaft C to be rotated with facility when the safe is elevated.

Instead of the counter-balances N N' being located between the rod B and ropes L L', as in Fig. 1, they may be placed at the sides of the room, or within the walls of the same, in either of which cases the rope should proceed horizontally from the sheaves M M', as seen in Fig 2; or the support B can be composed

of gas-pipe, and have a rope, P, passed down through it and attached to the pin d', which secures the annulus D to the shaft C, as represented in Fig. 4. The other end of the rope P can have a concealed weight attached thereto. The shaft C may have a number of shelves secured to it, as represented at E¹ E² E³ in Fig. 4.

In this illustration, the legs G are dispensed with, as they are not essential in all cases. The legs G may be fixed to the shaft C, so as to turn with the same, either to the right or left, or they may be free to rotate around said shaft.

I claim as my invention—

1. The within-described suspension safe or sideboard, consisting essentially of the support B, having the notches b, tubular slide C, carrying one or more shelves, E, the spring-catch H, the suspension-ring K, ropes L L', sheaves M M', and counter-balances N N', substantially as and for the purposes set forth.

2. The combination of the guided and counterbalanced slide C, carrying one or more shelves, E, and the folding legs G, attached to the bottom of the same by brackets F, substantially as specified.

3. The combination of the guided and counterbalanced slide C, carrying one or more shelves, E, the disk I, having the peripheral groove i, the screen J, and cord j, as and for the purpose described.

In testimony of which invention I hereunto set my hand.

JOSEPH RISSEL.
